A. TURNER ET AL.
WORK CENTERING DEVICE FOR MACHINE TOOLS.
FILED SEPT. 22, 1920.

UNITED STATES PATENT OFFICE.

ALBERT TURNER AND HOWARD WESLEY DUNBAR, OF WORCESTER, MASSACHUSETTS,
ASSIGNORS TO NORTON COMPANY, OF WORCESTER, MASSACHUSETTS, A CORPORA-
TION OF MASSACHUSETTS.

WORK-CENTERING DEVICE FOR MACHINE TOOLS.

Application filed September 22, 1920. Serial No. 412,063.

To all whom it may concern:

Be it known that we, ALBERT TURNER and HOWARD W. DUNBAR, citizens of the United States of America, residing at Worcester, 5 in the county of Worcester and State of Massachusetts, have invented certain new and useful Improvements in Work-Centering Devices for Machine Tools, of which the following is a full, clear, and exact specification.

Our invention relates to work-centering devices for machine tools, such as grinding machines or lathes, and more particularly to an attachment for converting a fixed or 15 "dead" center into a running or "live" center.

In grinding operations the work is usually supported between centers held against rotation, commonly termed "dead" centers, arranged on the head and foot stocks of the machine, one of said centers being longitudinally movable to allow of placing the work into position. Suitable dogging means are clamped to the work and the work is rotated 25 by engagement of the dog with a driver on the head stock. In some work, however, such as the grinding of twist drills, since the work is not adapted to be supported on the usual fixed centers, it becomes necessary to 30 provide a special running center construction on the headstock to engage and drive the work. It has been proposed to use a special running center and driver on a fixed center for this purpose, but the devices heretofore constructed have been open to the objection that, since no adequate provision has 35 been made to take up the wear due to side thrust caused by the action of the tool on the work, after a short time side play ensues with a consequent marring of the work.

It is an object of our invention to overcome these difficulties by mounting a running center attachment on a fixed center in such a way that the wear is automatically 45 taken up and the running center held against side play at all times by the thrust exerted thereon by the work, whereby it will always run true, regardless of the wear, and thus produce work of a uniform quality.

With this and other objects in view, as

will appear from the following disclosure, our invention resides in the combination of parts set forth in the specification and covered by the claims appended thereto.

Reference being had to the accompanying 55 drawings in which like numerals indicate like parts:

Figure 1 is a sectional view showing our running center attachment mounted in place on the headstock of a grinding machine;

Fig. 2 is a front elevation thereof showing the driver pin but omitting the other parts of the headstock shown in Fig. 1;

Fig. 3 is a fragmentary sectional view of a modified centering means adapted for 65 work having a center hole; and

Fig. 4 is a side elevation of another form of centering and work driving means which may be used in connection with our invention.

In the practice of our invention, we provide a running center attachment for use on the headstock of a machine tool to hold the work true. The centering device is preferably mounted on spaced bearings, one of 75 which takes both the end and side thrusts of the work, and, in our preferred arrangement, this latter bearing is tapered and arranged adjacent the work-engaging part of the attachment. This attachment is rotated by a suitable driver on the rotatable face plate which may be, and preferably is, the same driver as that which rotates the work when the latter is supported on fixed centers. Where desirable to use a running 80 center on the tailstock, our attachment can obviously be used there as well as on the headstock.

In the specific embodiment of our invention selected for illustration we have shown 90 our improved centering device as applied to a headstock of a usual construction provided with a spindle 1 having a central opening 2 into which the tapered shank 3 of the fixed center 4 is driven. The usual 95 face plate 5, we have shown connected by suitable means, such as the screws 7, with a gear 6, this gear being mounted for rotation through its wide bearing hub 8 and a bearing bushing 9 on the forward end of the 100

spindle 1. The means for retaining the gear and bushing in place on the spindle may consist of an annular plate 10 connected to the spindle as by screws 11. The connected 5 gear and face plate may be driven from the usual shaft carrying a cone pulley arranged on the headstock. The face plate 5 carries the usual driver pin 13 adjustably mounted in radially extending T-slots 14 thereon.

10 In carrying out our invention we preferably substitute for the usual fixed center a center 4 having a flange 15 thereon intermediate its ends, but we may leave the usual center in place and mount our running center attachment thereon, if desired. From 15 the flange 15 forward, the center has the usual cylindrical form which terminates in a conical point 16. On this forward portion, we mount our running center attachment 20 17 which may be provided with a radial flange 18 having a slot 19 to receive the driver pin 13. This flanged construction insures a balanced device well adapted for connecting the attachment to the driver 25 pin 13.

The attachment consists essentially of a hollow body portion 20 rotatably supported on the center 4 by means of spaced bearings 21 and 22 and provided with some form of 30 work-centering means 23, and if used on the headstock as shown, with a work-driving means such as the dogs 24. We have shown the body 20 of the attachment as being of generally conical shape and formed with 35 aligned cylindrical bores 25, 26 and 27 of increasing diameter from the front of the attachment to the back and forming the rearwardly facing shoulders 28 and 29. The forward bore 25 is relatively short and receives 40 the tightly fitting bearing bushing 30 of hard metal such as hardened steel. This bushing is provided at its rearward end with a conical opening to receive the conical point 16 of the center pin and thus forms a combined radial and end thrust bearing 45 adapted to take up for wear and maintain the work accurately centered at all times. This bushing 30 has formed on its rearward end an outwardly extending flange 31 which 50 engages the shoulder 28 to prevent forward movement of the bushing under the end thrust. The centering means 23 is shown (Fig. 1) in the form of a conical depression formed in the bushing 30 to receive work 55 having a mating shaped end, such as a twist drill, but it is obvious that this may take on a variety of forms, depending upon the nature of the work being operated on.

In Fig. 3 we have shown a modified form 60 in which the centering means 23' on the bushing 30' is in the form of a conical point, such as is usually employed in connection with work having a center hole. The body 20' of the attachment is shown somewhat 65 modified in this figure, but the principle of

operation is the same. The bushing 30' is driven into the bore 25' corresponding to the bore 25 in Fig. 1 and a flange 31' on the bushing bears against the shoulder 28' on the body of the attachment. 70

In Fig. 4 we have shown a still further modification of the bushing which we may employ. The bushing 30" shown in this figure has a centering means 23" in the form of a pyramid. This form is especially 75 adapted for centering and driving small work having center holes of mating form, thus avoiding the use of separate work-driving means such as the dog 24 shown in Fig. 1. 80

The central bore 26 is of a diameter somewhat larger than the center 4 to avoid frictional engagement therewith. To further minimize friction the bearing 22 may be a ball bearing as shown, consisting of the inner and outer ball raceways 32 and 33 and the balls 34. When the parts are in place the inner raceway 32 fits tightly onto the cylindrical portion of the center and bears against the flange 15 thereon. This bearing 90 is housed in the enlarged bore 27 of the attachment, the rear end of which is preferably closed to exclude dust and dirt from the bearing by an annular plate 35 suitably connected as by screws 36 to the rear side of 95 the attachment. This plate also serves to hold the ball bearing in place in body 20. To allow endwise movement of the attachment to automatically take up for wear in the conical bearing 21, we provide a close 100 sliding fit between the outer ball raceway 33 and the wall of the bore 27, and a clearance space 37 between the shoulder 29 and the ball bearing raceways.

It will be apparent from this construction, 105 since the work is always held against the center by a certain pressure which, especially in the case of relatively small work, is usually exerted on the tailstock spindle by a spring, that any wear in the conical bearing 21 will be automatically taken up, thus avoiding all side play, which would have a tendency to injure the work. It should also be noted that the work-engaging part 23 is located at a comparatively short distance 110 from the bearing 21, so that, even if the rear ball bearing should, in time, become worn, the effect on the work would be almost negligible. 115

Having thus described our invention, what 120 we claim as new and desire to secure by Letters Patent is:

1. A work-centering and driving device for machine tools, comprising a fixed center, a running center attachment rotatably 125 mounted thereon, a work driver on said attachment and spaced radial bearings between said fixed center and said attachment, one of said bearings comprising cooperating tapered surfaces on said center and attach- 130

ment to take the end thrust and avoid side play between the fixed center and the running center attachment.

2. A work-centering and driving device for machine tools, comprising a fixed center, a running center attachment rotatably mounted thereon and having a work-engaging part, and spaced radial bearings between said center and said attachment, one 5 of said bearings comprising cooperating conical surfaces on said center and attachment adjacent the work-engaging part on the latter to take the end thrust and avoid side play between the fixed center and the 10 running center attachment.
3. A work-holding center for machine tools, comprising a fixed center, a rotatable centering means having a work-holding part mounted on said fixed center, and 15 spaced bearings for said means, one of said bearings comprising a tapered bearing adjacent said work-holding part to take radial and end thrusts and the other comprising a radial bearing allowing endwise movement 20 of said centering means to take up the wear in the tapered bearing.
4. A centering device for the headstock of machine tools, comprising a fixed center, a 25

running center attachment rotatably mounted thereon, and spaced bearings for said attachment, one of said bearings comprising cooperating tapered bearing surfaces between the end of said center and said attachment and the other of said bearings comprising an anti-friction bearing allowing 30 endwise movement of the attachment to take up the wear in the tapered bearing.

5. A centering device for the headstock of machine tools, comprising a fixed center, a rotatable centering attachment having a 35 work-holding and driving means mounted thereon, spaced bearings for said attachment, one of said bearings comprising a tapered bearing adjacent said work-holding means to take both radial and end thrusts, the other comprising a radial ball bearing arranged so as to allow endwise movement between said bearing and the rotatable attachment to take up for wear in the tapered bearing, and means for driving the rotatable 40 attachment.

Signed at Worcester, Massachusetts, this 45
20th day of Sept., 1920.

ALBERT TURNER.
HOWARD WESLEY DUNBAR.
